UNITED STATES PATENT OFFICE.

JACOB ZIMMERMAN, OF PHILADELPHIA, PENNSYLVANIA, ASSIGNOR TO PARAMOUNT KNITTING MILLS, OF PHILADELPHIA, PENNSYLVANIA, A CORPORATION OF PENNSYLVANIA.

SWEATER.

Application filed February 19, 1927. Serial No. 169,647.

The present invention is concerned with the provision of a coat type sweater so arranged that it may be neatly worn when buttoned up in several positions, and which 5 in all positions of adjustment, will snugly fit the wearer.

Most of the coat type collar sweaters at present in common use, are provided with shawl collars. When the sweater is open at 10 the neck, the collar fits snugly at the back of the neck, but presents an extremely clumsy appearance at the front. If the sweater collar is knitted so that it will lie down flatly at the front, the result is that 15 the collar bulges out at the back, and in either instance a poor fit is had.

In accordance with the present invention, I have provided a coat type sweater with a distinctively novel collar construction. The 20 use of the straight shawl collar is eliminated, and a collar having lapels is substituted, this collar being so shaped and connected to the rest of the sweater, that it will lie flat when opened at the neck, and snugly 25 and accurately fit the wearer. The collar may be buttoned up about the throat, and folded over, in which position, a neat, snug fit is still had; or in extremely stormy weather, the collar may be turned up about 30 the ears and buttoned across the mouth of the wearer without in any way distorting the shape of the garment.

The conventional manner of constructing shawl collar sweaters has prohibited the use 35 of lapels, and any attempt to form such a collar into the lapel type would simply add to its already ill fitting appearance. I have accomplished the desired results by a radical change in the collar design and construction, 40 and the manner of attaching it to the remainder of the sweater.

With the above noted and other objects in view, the invention consists in certain novel features of construction and combinations 45 and arrangements of parts, as will be more fully hereinafter set forth and pointed out in the claims. The invention may be more fully understood from the following description in connection with the accompanying drawings, wherein—

Fig. 1 is a perspective view showing the

sweater of the present invention in applied position with the collar turned back and the sweater open at the neck.

Fig. 2 is a similar view showing the collar 55 buttoned up under the wearer's chin.

Fig. 3 is a similar view showing the collar turned up about the ears to afford substantial protection to the wearer's face and head in inclement weather.

Fig. 4 is a perspective view of the sweater, 60 showing the same removed, unbuttoned, and fully extended.

Fig. 5 is a plan view of the collar piece used in the construction of the sweater of 65 Figs. 1 to 4.

Fig. 6 is a fragmentary perspective view 70 illustrating a modification, with the collar piece and sweater body separated to illustrate the manner in which they interfit.

Fig. 7 is an inside plan view of the sweater 75 of Fig. 6, showing the collar applied.

The sweater of Figs. 1 to 5 is preferably of the shaker type, knitted throughout, and including a unitary back section 10 and 80 front sections 11 turned up in the conventional manner at their lower edge to define a tubular hem or border 12. The front sections 11 and the rear section 10 are unconnected at the usual armhole portions 13 into 85 which the sleeves 14 are knitted, sections 11 and 12 being then integrally connected along a portion of the shoulder lines 15 from the armholes inwardly.

Attached to the upper edge of the rear 85 section 10, as by knitting, or in any other suitable manner, is the substantially straight edge 16 of a relatively deep collar section 17, the free edge 18 of which is slightly curved as seen in Figs. 4 and 5, and the side edges 90 of which extend in substantial parallelism as at 19 for a short distance from the line 18, and then taper inwardly at 20, terminating in short, substantially parallel edges 21. It will be noted from Fig. 1 and Fig. 4 95 that the corners defined by the edges 18 and 19 provide projecting ears 22 in the finished sweater.

It will be noted that the sections 11 and 100 section 10 are not united throughout the entire length of their shoulder line forming upper edges, but that the inner or forward

portions of the upper edges of the front sections overlap the corners of the collar section 17 defined by the edges 16 and 21. Thus the upper inner corners 23 of the front sections, which for the sake of convenience, are lapped over the lower corners of the collar section 17 and knitted thereto to provide an integral structure.

The lapel is completed by tapering wing sections 24 integral with band sections 25. The wing sections 24 are secured to the edges of the front sections 11 and to the slanting edges 20 of the collar section 17, corners 24^a of the wings cooperatively defining with the corners 22 of the section 17, V-shaped notches 26. Sections 24 at their widest portions, to wit: Their upper edges, are of less width than the adjacent lateral edges of sections 17 to which they are connected.

As is customary in the art, the bands 25 of the wing sections 24 are connected to the inner or free edges of the sections 11 and carry the usual buttonholes 27 and buttons 28.

This collar construction in which the inner upper edges of the front sweater sections are lapped over the corners of the collar piece, permit the junction lines 20, 20 of sections 17 and 24 to be thrown well forwardly on the wearer's chest, instead of at the shoulder lines, and consequently there is assured, a snug fit when the collar is folded back and opened at the throat as in Fig. 1.

If, the side edges of the collar section 17 were formed as continuations of the shoulder lines 15, the lapel portions of the collar would not lie down properly as will be readily understood, since the collar would not naturally fold upon the proper lines to cause the lapel to naturally assume a flat position. In the ordinary shawl collar sweater, the reason for the rolling and ill fitting of the front portions of the shawl collar is the fact that the rear deep section joins the front sections along a line of union coincident with the shoulder lines of the sweater.

In Fig. 2, I have shown the sweater buttoned up under the wearer's throat by engaging a loop 30 with a button 31 on the collar section 17. With the sweater thus buttoned, the wing portions 24, 24 are overlapped, and the free projecting corners 22 of the collar section 17 may be folded downwardly over the overlapped wings to provide a neat collar arrangement. In Fig. 3 I have shown this free portion of the main collar section 17 turned upwardly in such a manner that the mouth, chin and ears, as well as the back of a wearer's head are fully protected against the weather.

In Figs. 6 and 7 I have illustrated a sweater of a slightly different construction, but which when assembled accomplishes exactly the same results. Here, that portion of

the collar section 17^a which in Fig. 4 is overlapped by the front section 11, is cut away as at 40, providing two collar edges 41 and 42 which may be sewed to the free corner forming edges 42 and 43 of the front 70 sweater sections. The construction of the finished sweater is substantially the same, except that the overlap has been omitted.

Obviously, various changes and alterations might be made in the general form and arrangement of parts described without departing from the invention. Hence I do not wish to limit myself to the details set forth, but shall consider myself at liberty to make such changes and alterations as fairly fall 80 within the spirit and scope of the appended claims.

I claim:

1. A knitted coat sweater including connected back and front body sections, a relatively deep turnover collar section joined to the upper edge of the back body section, relatively narrow tapering lapel forming wing sections secured to the free forward inner edges of the front sections, and to the 90 lateral edges of the relatively deep rear collar section, the back body section and front body sections being separated at the inner ends of their upper shoulder line forming edges, and said free portions of the upper edges of the front sections being secured to the deep collar section at points disposed well rearwardly of the lines of union of said collar section and lapel forming wing sections.

2. A knitted coat sweater including integrally connected back and front body sections, a relatively deep turnover collar section joined to the upper edge of the back body section, relatively narrow tapering lapel forming wing sections secured to the free forward inner edges of the front section, and to the lateral edges of the relatively deep rear collar section, the back body section and front body sections being separated at the inner ends of their upper shoulder line forming edges, and said free portions of the upper edges of the front sections being secured to the deep collar section at points disposed well rearwardly of the lines of union of said collar section and lapel forming wing sections, the corners of the front sections defined by their free shoulder line edges and the upper ends of their forward inner edges overlapping the corners of the collar section, and said overlapping corner portions being connected together.

3. A knitted coat sweater including integrally connected back and front body sections, a relatively deep turnover collar section joined to the upper edge of the back body section, relatively narrow tapering lapel forming wing sections secured to the free forward inner edges of the front sections, and to the lateral edges of the 125

tively deep rear collar section, the back body section and front body sections being separated at the inner ends of their upper shoulder line forming edges, and said free portions of the upper edges of the front sections being secured to the deep collar section at points disposed well rearwardly of the lines of union of said collar section and lapel forming wing sections, the lower forward corners of the collar section being cut away to accommodate the upper inner corners of the front body sections.

4. A knitted coat sweater including integrally connected back and front body sections, a relatively deep turnover collar section joined to the upper edge of the back body section, relatively narrow tapering lapel forming wing sections secured to the free forward inner edges of the front sections, and to the lateral edges of the relatively deep rear collar section, the back body section and front body sections being separated at the inner ends of their upper shoulder line forming edges, and said free portions of the upper edges of the front sections being secured to the deep collar section at points disposed well rearwardly of the lines of union of said collar section and lapel forming wing sections, the lateral edges of the collar section projecting well beyond the adjacent edges of the lapel forming wing sections to which they are connected, said connected edges diverging near their outer ends to form V-shaped notches, and permit folding back of the outer portion of the collar independently of the folding back of the lapel forming wing sections.

5. A knitted coat sweater including integrally connected back and front body sections, a relatively deep turnover collar section joined to the upper edge of the back body section, relatively narrow tapering lapel forming wing sections secured to the free forward inner edges of the front sections, and to the lateral edges of the relatively deep rear collar section, the back body section and front body sections being separated

rated at the inner ends of their upper shoulder line forming edges, and said free portions of the upper edges of the front sections being secured to the deep collar section at points disposed well rearwardly of the lines of union of said collar section and lapel forming wing sections, the lateral edges of the collar section projecting well beyond the adjacent edges of the lapel forming wing sections to which they are connected, said connected edges diverging near their outer ends to form V-shaped notches, and permit folding back of the outer portion of the collar independently of the folding back of the lapel forming wing sections.

6. A knitted coat sweater including integrally connected back and front body sections, a relatively deep turnover collar section joined to the upper edge of the back body section, relatively narrow tapering lapel forming wing sections secured to the free forward inner edges of the front sections, and to the lateral edges of the relatively deep rear collar section, the back body section and front body sections being separated at the inner ends of their upper shoulder line forming edges, and said free portions of the upper edges of the front sections being secured to the deep collar section at points disposed well rearwardly of the lines of union of said collar section and lapel forming wing sections, the lateral edges of the collar section projecting well beyond the adjacent edges of the lapel forming wing sections to which they are connected, said connected edges diverging near their outer ends to form V-shaped notches, and permit folding back of the outer portion of the collar independently of the folding back of the lapel forming wing sections.

JACOB ZIMMERMAN.
